UNITED STATES PATENT OFFICE

158,526

MIRROR SUPPORTING FRAME

Edwin G. Staude, Minneapolis, Minn.

Application October 26, 1948, Serial No. 149,313

Term of patent 3½ years

(Cl. D33—9)

To all whom it may concern:

Be it known that I, Edwin G. Staude, a citizen of the United States, residing at Minneapolis, in the county of Hennepin and State of Minnesota, have invented a new, original, and ornamental Design for Mirror Supporting Frame, of which the following is a specification, reference being had to the accompanying drawing, forming part thereof.

Fig. 1 is a front elevational view of a mirror supporting frame showing my new design, the mirror and its trunnions being shown in broken lines.

Fig. 2 is a plan view and

Fig. 3 an end view of the frame.

Fig. 4 is a transverse sectional view taken in the plane of line 4—4 of Fig. 2.

The dominant feature of the design resides in the portions shown in full lines in the drawings.

I claim:

The ornamental design for a mirror supporting frame, substantially as shown and described.

EDWIN G. STAUDE.
